UNITED STATES PATENT OFFICE.

WILLIAM H. STANLEY, OF ANACORTES, WASHINGTON.

INSECT-TRAP.

1,294,184.

Specification of Letters Patent.

Patented Feb. 11, 1919.

Application filed June 29, 1918. Serial No. 242,533.

To all whom it may concern:

Be it known that I, WILLIAM H. STANLEY, a citizen of the United States, residing at Anacortes, in the county of Skagit and State 5 of Washington, have invented certain new and useful Improvements in Insect-Traps, of which the following is a specification, reference being had to the accompanying drawings.

10 This invention relates to certain improvements in insect traps and has relation more particularly to a device of this general character which is included in a screen door structure and it is an object of the invention 15 to provide a novel and improved device of this general character having effective means whereby flies or the like may be readily captured.

It is also an object of the invention to 20 provide a device of this general character wherein a movable cage is employed together with a support carried by a screen door or the like upon which the cage is mounted and wherein means are employed 25 for effectively holding the cage in applied position upon the support.

The invention consists in the details of construction and in the combination and arrangement of the several parts of my invention 30 whereby certain important advantages are attained and the device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein:

Figure 1 is a view partly in elevation and partly in section illustrating an insect trap constructed in accordance with an embodiment of my invention;

45 Fig. 2 is an enlarged vertical sectional view taken through the upper end portion of the device as illustrated in Fig. 1;

Fig. 3 is a fragmentary view in perspective of the supporting member as herein embodied.

50 As disclosed in the accompanying drawings 1 denotes the vertical stiles of a screen door frame and interposed between said stiles at a point in close proximity to the top strip 2 of the door frame is a supporting member S formed preferably of a thin me-

tallic plate and which is substantially in the form in cross section of an inverted V. The apex portion of the supporting member S is provided with the elongated openings 3 and 60 the opposite end portions of the supporting member S bridge the inner marginal portions of the vertical stiles 1 and are suitably anchored thereto as indicated at 4. The sides 5 of the supporting member S extend 65 beyond the opposite faces of the door frame and secured to the lower marginal portion of the member S at the inner side of the door frame is the upper edge portion of the screen fabric F coacting with the lower portion of the door frame while the lower edge portion of the screen fabric F' coacting with the upper portion of the door frame is secured to the lower marginal portion of the side 5 of the supporting member S extending 70 beyond the outer face of the door frame.

C denotes a cage of a length substantially equal to the distance between the vertical stiles 1 of the door frame and said cage includes a bottom plate 6 having its portion at 80 substantially its transverse center in the form of an inverted V with the apex portion thereof provided with the elongated openings 7. Secured to the opposite longitudinal marginal portions of the bottom 6 85 and the marginal portions of the end pieces 8 of the cage is the screen fabric 9. The cage C is adapted to be mounted upon the supporting member S and when applied the V-shape portion of the bottom 6 receives the 90 supporting member S.

Adjacent each end of the supporting member S is a transversely disposed strip 10 preferably of wire and which may be secured to the member S in any desired manner. The 95 opposite end portions of the strip 10 are continued by the upwardly directed extensions 11 which are adapted to straddle the cage C when the same is mounted upon the support S whereby effective means are provided to effectively hold the cage C to the support S. The free extremities of the extensions 11 terminate in the upstanding portions 12 one of which being of loop formation and having interlocked therewith a 100 ring member 14. The member 14 is adapted to pass over the second portion 12 for holding the extensions 11 in locked engagement with the cage C. When it is desired to remove the cage C it is only necessary to disengage the ring 14 from the second portion 12 and separate the extensions 11 and then 110

sufficiently separate or spread said extensions 11. In order to empty the cage C of its contents an end piece 8 is removed.

- Secured to the inner marginal portions of the vertical stiles 1 and adjacent the support S are the outwardly directed wings 15 substantially diamond-shaped in form and secured to the free edge portions of said wings 15 is the fabric F' hereinbefore referred to.
- 10 The wings 15 and fabric F' produce a downwardly opening passage-way to facilitate the capture of the flies or other insects. When the flies or the like light upon the door it is their characteristic to alight with 15 their heads up. The heat from the room causes them to crawl upwardly. As they enter within the passageway a as afforded by the wings 15 and the fabric F' they will be guided into the trap.
- 20 As is particularly illustrated in Fig. 2 each of the strips 10 is anchored as at 16 to the inner face or edge of a vertical stile 1.

From the foregoing description, it is thought to be obvious that an insect trap constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. An insect trap comprising a frame, a support substantially in the form of an inverted V in cross section disposed across the frame, the apex portion of the support being provided with an opening, a fabric for closing the frame above the support and connected with the lower marginal portion of the support, a second fabric for closing the frame below the support and secured to the second longitudinal marginal portion of the support, a cage seatable upon the support and including a bottom having an inverted V-shape portion to receive the support, the apex portion of the bottom of the cage being provided with an opening to register with the opening in the

support, and means for locking the cage to the support.

2. An insect trap comprising a frame, a support substantially in the form of an inverted V in cross section disposed across the frame, the apex portion of the support being provided with an opening, a fabric for closing the frame above the support and connected with the lower marginal portion of the support, a second fabric for closing the frame below the support and secured to the second longitudinal marginal portion of the support, a cage seatable upon the support and including a bottom having an inverted V-shape portion to receive the support, the apex portion of the bottom of the cage being provided with an opening to register with the opening in the support, upstanding extensions at opposite sides of the support adapted to straddle the cage when the cage is mounted upon the support, and locking means co-acting with the extensions for holding the same in locking engagement with the cage.

3. An insect trap comprising a frame, a support substantially in the form of an inverted V in cross section disposed across the frame, the apex portion of the support being provided with an opening, a fabric for closing the frame above the support and connected with the lower marginal portion of the support, a second fabric for closing the frame below the support and secured to the second longitudinal marginal portion of the support, a cage seatable upon the support and including a bottom having an inverted V-shaped portion to receive the support, the apex portion of the bottom of the cage being provided with an opening to register with the opening in the support, and means for locking the cage to the support, laterally extended wings carried by the frame adjacent the support, the second named fabric being secured to the outer marginal portions of said wings, said wings and fabric affording a passage-way leading to the support.

In testimony whereof I hereunto affix my signature in the presence of two witnesses.

WILLIAM H. STANLEY.

Witnesses:

EARL R. LOVELL,
ANNA L. McDANIEL.
